US0D1051740S

(12) **United States Design Patent** (10) Patent No.: **US D1,051,740 S**
(45) Date of Patent: ** Nov. 19, 2024

(54) **HEATING VENTILATION AND AIR CONDITIONING CONTROLLER**

(71) Applicant: **RESEARCH PRODUCTS CORPORATION**, Madison, WI (US)

(72) Inventors: **John Genova**, Madison, WI (US); **Casey Klock**, Madison, WI (US); **John Ortman**, Madison, WI (US); **Ryan Rommelfanger**, Madison, WI (US)

(73) Assignee: **Research Products Corporation**, Madison, WI (US)

(**) Term: **15 Years**

(21) Appl. No.: **29/884,551**

(22) Filed: **Feb. 13, 2023**

Related U.S. Application Data

(62) Division of application No. 29/762,949, filed on Dec. 18, 2020, now Pat. No. Des. 977,996.
